UNITED STATES PATENT OFFICE.

HARRY MORRIS, OF DETROIT, MICHIGAN, ASSIGNOR OF ONE-HALF TO LE GRAND INGERSOLL, OF SAME PLACE.

DESIGN FOR A TRACK OR WAY FOR AMUSEMENT-RAILWAYS.

SPECIFICATION forming part of Design No. 34,635, dated June 4, 1901.

Application filed April 12, 1901. Serial No. 55,558. Term of patent 14 years.

To all whom it may concern:

Be it known that I, HARRY MORRIS, a citizen of the United States, residing at Detroit, in the county of Wayne and State of Michigan, have invented and produced a new and useful Design for a Track or Way for an Amusement-Railway, of which the following is a specification, reference being had to the accompanying drawings, forming part thereof.

10 Figure 1 is a view in perspective of a track for an amusement-railway, showing my new design. Fig. 2 is a plan view of the same.

As shown in the drawings, the leading or material feature of my design consists of a track for an amusement-railway formed of 15 circular end portions and intermediate side portions connective of the end portions, each of said side portions being composed of two straight diagonal runs merging into each 20 other and into the circular end portions in planes tangential thereto in plan view without the intervention of a reverse curve, the whole being arranged to form an endless structure disposed in a plurality of superposed 25 elongated spiral convolutions *a* and in a loop

b, connective of the upper and lower convolutions, the bight of which loop extends out beyond the convolutions. The loop *b*, connective of the lowermost and uppermost convolutions, is formed with a straight end portion *f*, gradually curving into the legs *c* *d*, forming the sides of the loop, the leg *d* of which just before it merges into the uppermost convolution being formed, in plan view, with a straight portion *d'* at a slight lateral 30 inclination to the leg proper. A series of dips *e* are formed in the track, one in each side portion of the respective convolutions and one in the leg *c* of the loop and one in the portion *d'* of the leg *d*.

Having thus described my invention, I claim—

The design for a track or way for an amusement-railway, as herein shown and described.

In testimony whereof I affix my signature 45 in presence of two witnesses.

HARRY MORRIS.

Witnesses:

OTTO F. BARTHEL,
JOSEPH A. NOELKE.
